PROFILING MACHINE

Johannes Roloff, Schonebeck, and Bernd Zingsheim, Weimar, Germany, assignors to Junkers Flugzeug - und - Motorenwerke Aktiengesellschaft, Dessau, Germany, a corporation of Germany

Application July 18, 1939, Serial No. 285,048
In Germany July 21, 1938

20 Claims. (Cl. 90—13)

This invention relates to improvements in profiling machines, and refers primarily to such machines intended to finish various structural sections and the like as the latter are fed there-
5 through.

It is an object of the invention to provide profiling machines wherein structural sections and the like are attached to a template and shaped longitudinally, either straight or tapered, to conform to the profile of the template. Thus the machine is primarily adapted for the production of a quantity of similar workpieces.

Another object of the invention is to provide such a profiling machine wherein the workpiece and the template attached thereto are fed longitudinally between rotary tools; wherein followers extend from carriages in which the tools are mounted; and wherein means are provided for retaining the followers in constant contact with opposite sides of the template as the latter is fed between them, either when the template is straight or longitudinally tapered, either vertically, or horizontally, or both.

A further object of the invention is to provide 25 a profiling machine having work supports including pressure rollers which are automatically moved upwardly and inwardly to engage opposite corners of the work and hold it for movement in a longitudinal direction only.

Another object of the invention is to provide 30 a profiling machine wherein the tools are rotated about axes which are inclined to one another and to the path of movement of the work so that the said tools may operate simultaneously upon different portions of the work.

Another object of the invention is to provide a profiling machine wherein means are provided for materially reducing the possibility of chips coming between the template and the followers or interfering with the operation of other portions of the machine, when the rotary tools employed are in the form of stock removing cutters; and wherein means are provided for free discharge of such chips.

Another object of the invention is to provide 45 a profiling machine wherein a workpiece may be longitudinally shaped by any preferred type of rotary tools, either stock removing cutters or rolls.

Another object of the invention is to provide 50 a profiling machine which is relatively cheap and simple to manufacture, and with which workpieces may be much more cheaply and expeditiously processed.

Having thus briefly set forth some of the ob- 55 jects and advantages of the invention, we will

now proceed to describe one preferred general embodiment thereof and one modified form of actuating the pressure rollers, with the aid of the accompanying drawings, in which:

Figure 1 is a perspective view of the machine. 5

Figure 2 is a transverse section through one of the pressure members mounted in the base.

Figure 3 is a transverse section showing a modified form of pressure member.

Figure 4 is a transverse view showing the cutters and the work in section; the cutters in this instance being arranged to machine all the edge faces of a T-shaped structural section.

Figure 5 is a similar view showing cutters machining the undersides of the flanges and both 15 sides of the web of a T-shaped section.

Figure 6 is a diagram showing the sequence of operations and the remaining stock left on a T-shaped structural section.

Figure 7 is a perspective view showing the tem- 20 plate and the work supported thereunder.

Figure 8 is a diagram showing the operation of the machine.

Figure 9 is a diagram showing a piece of flat stock and the material removed therefrom. 25

Figure 10 is a diagrammatic view showing the arrangement of cutters operating on the edge faces of a piece of flat stock, and

Figure 11 is a diagrammatic view showing a cutter machining across the entire width of one 30 side thereof.

Referring first to Figure 1, 1 designates the base of the machine over the table 3 of which a work guide 2 is provided. The underside of the latter is maintained parallel with the table 3 and at its 35 extremities has depending and transversely opposed frames 4 through which the extremities of the work extends.

Extending downwardly from the frames 4, preferably centrally of their width are pillars 5 which are vertically movable in appropriate guide openings 5a formed in the base 1.

Mounted horizontally in the bed 1 is a spindle 7 provided at one extremity with an operating wheel 9 and having pinions 8 fixed thereon each of which is in engagement with a rack 6 which 40 extends vertically upon one of the said pillars 5.

Thus by rotation of the handwheel 9 the height of the work guide 2 above the table 3 may be adjusted. To prevent accidental vertical movement of the guide 2 above the table 3 a ratchet wheel 10 is secured upon 45 the spindle 7 for engagement with a suitably mounted dog 11.

The work 14, shown in the drawings in the form of a T-shaped structural section, is secured as by screws 91 to the underside of a template 15 50 55

the upper side of which is held against double flanged rollers 18 rotatably supported from the work guide 2, and a plurality of supports 16 and 17 are employed for engaging the underside of the work 14 and holding the latter and the template 15 for longitudinal movement between them and the said rollers 18. Since both the supports 16 and 17 are the same I will describe the embodiment of one of them shown in Figure 2.

10 Projecting downwardly through an opening formed in the table 3 is a cylinder 22 which, in the present instance, is shown welded to the underside of the said table. Mounted for movement in the cylinder 22 is a plunger 21 having a rest 20 extending laterally on both sides at its upper extremity. Rotatably mounted at its opposite ends in upturned portions 20a of the rest 20 is a spindle 23 provided with a relatively steep thread towards each extremity. The thread towards one extremity is right handed and towards the other extremity left handed. Secured around the spindle 23 centrally of its length is a pulley 31. Two opposed slides 24 are mounted upon the rest 20 for transverse movement towards and from one another. Extending downwardly from each slide 24 is an apertured projection 25 through which the spindle 23 passes, and provided in the said slide 24 and projections 25 are pins 26 which engage the right and left hand thread respectively on the spindle 23.

30 Supported for rotation in each slide 24 is a pressure roller 28. The axes of these rollers are inclined to the work so that the outwardly directed V-shaped faces of the rollers contact portions of both the base and the web of the T-shaped work 14. Resting against the base of the plunger 21, which is apertured, is one extremity of a spring 30 the other extremity of which rests upon the base of the cylinder 22, which is also apertured. The spring 30 tends to force the plunger 21 upward and thus move the pressure rollers vertically towards the work.

40 One extremity of a rope 32, in each support 16 and 17, is wound around a spool 34 located beneath that support, and the spools are secured to a common shaft 35 (Figure 1) mounted for rotation in the base 1 and provided at one extremity with an operating wheel 36. By rotation of the latter both spools 34 are rotated simultaneously.

50 The rope 32 extends upwardly from its spool 34 through the apertured portions of the cylinder 22 and plunger 21 and passes around the pulley 31, its adjacent extremity being secured to one end of a coil spring 33 (Figure 1), which is strong enough to hold the rope taut and to cause rotation of the spindle 23. Consequently when the shaft 35 is rotated not only is the plunger 21 moved upwardly by the spring 30 but the spindle 23 is also turned so that both the slides 24 are moved towards one another, thus the central portions of the peripheries of the pressure rollers 28 are brought firmly into engagement with the corners of the work 14 formed between their opposite base flanges and the opposite sides of the web thereof. Provided around the plunger 21 is a clamping device, in the present instance in the form of a split ring 39, so that by rotation of a threaded lock rod 38 the plunger may be held against accidental vertical movement. It will be noted that the split ring 39 is housed between the underside of the table 3 and a flange formed within the cylinder 22 to prohibit its vertical movement. To prevent 70 rotary movement of the plunger 21 in the cylinder 75

22 a keyway 40 is formed in the latter to receive a key 41 carried by the said plunger.

In the modified support arrangement shown in Figure 3 liquid pressure is employed for its operation. A flexible belt 45 is attached at its extremities to the slides 24, passes around guide rollers 45a mounted upon the base 1 and also around a head 46 carried on one extremity of a piston rod 47. The slides in this case are urged apart by a spring 54. The rod 47 extends through 10 packing provided in the base of the plunger 21 around the opening formed in the latter and terminates in a piston 48 mounted for reciprocation in a smaller cylinder portion 49 formed in the lower extremity of the cylinder 22. Inlet and 15 outlet pipes 50 and 51 having valves 52 and 53 respectively therein are provided for the passage of liquid under pressure into and out of the cylinder 22 and open into the latter between the base of the plunger 21 and the piston 48. When the 20 inlet valve 52 is opened, and the valve 53 closed, liquid pressure is exerted upon the plunger 21 to raise the latter and the slides 24 thereon, and also upon the piston 48 to draw the rod 47 downwards thereby lowering the head 46 and drawing 25 the slides 24 towards one another against the tension of the spring 54 by pulling the elastic belt 45. Obviously when the valve 53 is opened and the liquid pressure released the weight of the plunger 21 and the slides 24 thereon causes these 30 parts to move downward and the elasticity of the spring 54 raises the piston 48.

35 A feed screw 63 is supported in the base 1 and extends transversely of the latter to cooperate with two transversely opposed carriages 61 and 62 35 on opposite sides of the machine. These carriages are moved towards and from one another along a path at right angles to the direction of travel of the work 14 by rotation of the said screw which is provided with right and left hand 40 threads respectively towards opposite extremities to obtain this relative movement. Here it may be also noted that the carriages are positioned between the supports 16 and 17.

45 Secured on one outwardly projecting extremity of the feed screw 63 is a handwheel 64, and fixed adjacent thereto on the said screw is a pulley 65. A rope 66 is wound around the latter and has one extremity secured thereto, and the opposite extremity of the rope is fastened to one end of a 50 coil spring 67. The other end of the latter is secured to one extremity of a threaded spindle 68 mounted for engagement with a cooperating thread in the base 1 and having an operating wheel 69 fixed on its outer extremity. By turning the spindle 68 tension on the spring may be either increased or reduced so that the pull exerted on the rope 66 tending to turn the feed screw 63 may be varied. The rope is so wound around the pulley 65 that the spring 67 tends to move 60 the carriages 61 and 62 towards one another, and is intended to maintain rotary tools 60, which in the present instance are shown in the form of cutters, mounted on the said carriages in proper contact with work which is to be longitudinally 65 tapered.

65 Mounted for rotation in the carriages 61 and 62 are spindles 70 which are inclined both to one another and also to the path of travel of the work 14, so that the rotary tools 60 secured thereon 70 may be simultaneously operated. On each carriage 61 and 62 a motor 71 is provided to drive the tool spindle 70 rotatably mounted thereon, as through a belt 72 passing around a pulley 71a on the shaft of the said motor and also around a 75

second pulley 13 on the tool spindle. As will be clearly seen from Figures 4 and 5 followers 75 and 76 project inwardly from the carriages 61 and 62 respectively to engage opposite sides of the template 15, and are retained thereagainst, particularly when longitudinally tapered templates are being moved between the said followers, by the mechanism including the rope 66 and spring 67 hereinbefore described.

10 A longitudinal feed is imparted to the template 15 and the workpiece 14 in the following manner. On the work guide 2 a housing 80 is provided having a shaft 82a rotatably mounted therein. On the latter a sprocket wheel 82 is secured which engages a chain 81 extending longitudinally along the top of the template 15 and secured to the extremities of the latter as by screws 92. The shaft 82a is suitably driven. In the present case a worm wheel 83 is provided thereon which meshes with a worm 84 mounted for rotation in the said housing 80 and having a sprocket wheel 84a suitably connected thereto. A chain 84b passes both around the sprocket 84a and also around a second sprocket 85a fixed 25 on the shaft 85 of a motor 86, the latter being mounted upon the said housing 80. Clearance for the passage of the chain 81 is provided beneath the double flanged rollers 18 so that it may pass freely thereunder. A downwardly and outwardly directed passage 87 is formed through the base 1 so that chips may fall freely therethrough when tools of the stock removing type shown in the drawings are being utilized.

30 In Figures 4 and 5 the tools shown are of the stock removing type. The cutters 60 and 60a, Figure 4, are adapted to remove stock from the edge faces of the work as shown at 60e and 60f respectively in Figure 6, and the cutters 60b, Figure 5, are adapted to finish the inner side of 35 the base and the sides of the web of the workpiece 14 as shown at 60g in Figure 6.

35 From the perspective view shown in Figure 7 it will be clearly seen that by making the template 15 of longitudinally increasing thickness 40 the depth of the workpiece 14 is longitudinally correspondingly decreased; and also that by longitudinally decreasing the width of the template 14 the width of the work is correspondingly decreased.

45 Referring to the diagram shown in Figure 8, if the workpieces are materially longer than the machine, as is usually the case, we prefer to utilize roller stands 90 to support its extremities for free passage thereover. It will also be noted 50 that the rotary tools 60 turn in the opposite direction to the pressure rolls on the supports 16 and 17 and the rollers 18 which are turned by movement of the workpiece 14 and the template 15.

55 The operation of the machine is briefly as follows: The workpiece 14 is first attached to the template 15, and the unit thus formed is inserted longitudinally into the machine through one of the frames 4. The supports 16 and 17 are then raised so that the lower corners of the work are engaged by the pressure rollers 28 and the template is forced into engagement with the rollers 18, which are positioned one over each of the said supports and one above the tools 60.

60 The operation of the supports whereby the pressure rollers 28 are moved upwardly and inwardly is fully described in the foregoing. The work guide 2 must meanwhile have been set at the required height for vertically positioning the work 65 14 relative to the rotary tools 60. The chain

which extends longitudinally of the template and is secured to both extremities thereof extends beneath the rollers 18 and in engagement with the sprocket wheel 82 so that upon operation of the motor 86 the work is fed through the machine. 5 The motors 71 drive the tools 60, and the spring actuated mechanism hereinbefore described retains the followers 75 and 76 in contact with opposite sides of the template 15 so that the work is profiled as required. 10

From the foregoing it will be clearly seen that we have devised a profiling machine by which work may be very speedily, and accurately processed to conform to the shape of the template, and that the machine may be equally successfully employed if either stock removing cutters or rolls are utilized.

What we claim is:

1. A profiling machine comprising a plurality of rollers some adapted to bear against a template 20 and some to bear against a workpiece secured thereto, said rollers being adapted to permit movement of the template and workpiece between them, means for feeding the template and workpiece between the rollers, rotary processing tools 25 mounted in the machine, and followers adapted to engage the template rigidly held relative to the axes of the tools.

2. A profiling machine comprising the combination set forth in claim 1, wherein automatic 30 means are provided for exerting pressure upon the rollers to retain the template and work firmly engaged between them for movement in a single plane.

3. A profiling machine comprising the combination set forth in claim 1, wherein the rollers to engage the workpiece are formed to engage opposite corners of the latter, and means tending to move these rollers towards one another and towards the other rollers. 35

4. A profiling machine comprising the combination set forth in claim 1, wherein automatic means are provided for retaining the followers in contact with the template. 40

5. A profiling machine comprising the combination set forth in claim 1, wherein automatic means are provided for retaining the followers in contact with opposite sides of the template, and the tools are positioned to operate on opposite sides of the workpiece. 45

6. A profiling machine comprising the combination set forth in claim 1, wherein carriages are mounted for movement on opposite sides of the machine, said tools and followers being supported on said carriages, and a common means 55 for moving both the carriages either towards or away from one another.

7. A profiling machine comprising the combination set forth in claim 1, wherein carriages are mounted for movement on opposite sides 60 of the machine, said tools and followers being supported by the carriages, a feed screw for moving both the carriages towards or away from one another, and automatic means adapted to rotate the feed screw and hold the followers in engagement with opposite sides of the template. 65

8. A profiling machine comprising the combination set forth in claim 1, wherein the means for feeding the template consists of a chain adapted to be secured to opposite extremities 70 thereof, a sprocket wheel in engagement therewith, and means for driving the sprocket wheel.

9. A profiling machine comprising the combination set forth in claim 1, wherein means are provided for adjusting the height of the rollers 75

75

against which the template is adapted to bear whereby the work may be set vertically relative to the tools.

10. A profiling machine comprising a base, a guide supported thereby, rollers carried by the guide, a plurality of supports mounted in the base, pressure rollers mounted on the supports adapted to engage a work piece and force a template secured thereto into engagement with the first named rollers, means in the supports adapted to force the pressure rollers towards the first named rollers and into engagement with the workpiece, means adapted to move the template, carriages mounted on the base, rotary tools in the carriages, and followers on the carriages adapted to contact the template.

11. A profiling machine comprising the combination set forth in claim 10, wherein the means adapted to force the pressure rollers is spring actuated.

12. A profiling machine comprising the combination set forth in claim 10, wherein the means adapted to force the pressure rollers is hydraulically actuated.

13. A profiling machine comprising a base, a guide supported thereby, rollers carried by the guide adapted to bear against one side of a template, supports mounted in the base, pressure rollers mounted in pairs in the supports adapted to engage a workpiece secured to the opposite side of the template, means adapted to force the pressure rollers towards the first named rollers to engage the workpiece and template between them, means adapted to force each pair of pressure rollers towards one another to engage opposite sides of the workpiece and hold the latter for movement in a straight line, means adapted to move in template, carriages mounted on the base, rotary tools mounted on the carriages, and followers on the carriages to coact with the template.

14. A profiling machine comprising the combination set forth in claim 13, wherein the means adapted to force the pressure rollers towards one another is spring actuated.

15. A profiling machine comprising the combination set forth in claim 13, wherein the means adapted to force the pressure rollers towards one another is hydraulically actuated.

16. A profiling machine comprising the com-

bination set forth in claim 13, including equalizing means connecting the means for moving each pair of pressure rollers towards one another and the means for moving said pressure rollers towards the first named rollers.

17. A profiling machine comprising a plurality of rollers adapted to bear against a template having a workpiece secured thereto, other rollers adapted to contact the opposite side of the workpiece, means adapted to feed the template and workpiece between the rollers, carriages mounted for movement angularly to the path of movement of the template, means for moving the carriages towards one another, means tending to operate the last named means, followers on the carriages adapted to engage opposite sides of the template, and a rotary tool mounted in each carriage, said tools being adapted to operate on opposite sides of the workpiece.

18. A profiling machine comprising a plurality of rollers adapted to bear against a template having a workpiece secured thereto, other rollers adapted to contact the opposite side of the workpiece, means for varying the transverse distance between said rollers and said other rollers to engage the template and workpiece between them, carriages mounted for movement angularly to the path of movement of the template, means for moving said template in one direction, a feed screw coacting with the carriages, spring actuated means adapted to rotate the feed screw and move the carriages towards opposite sides of the work, followers on the carriages adapted to be held in contact with opposite sides of the template by said spring actuated means, and rotary tools mounted in said carriages.

19. A profiling machine comprising the combination set forth in claim 1, wherein the rotary tools are angularly disposed to one another and are adapted to process the work simultaneously in different planes.

20. A profiling machine comprising the combination set forth in claim 10, wherein the rotary tools are stock removing cutters, and said base having a passage formed therein extending from beneath the tools through which cuttings are adapted to pass.

JOHANNES ROLOFF. 50
BERND ZINGSHEIM.
